UNITED STATES PATENT OFFICE.

DANIEL BELCHER, OF MINNEAPOLIS, MINNESOTA, ASSIGNOR TO BEMIS BRO. BAG CO.,
OF MINNEAPOLIS, MINNESOTA, A CORPORATION OF MISSOURI.

BAG-FILLING APPARATUS.

Application filed February 21, 1927. Serial No. 169,859.

This invention relates to a method of and apparatus for filling bags. The invention is particularly applicable to that class of bag filling mechanisms which include a filling 5 spout, and a bag-supporting platform movable toward and away from the spout in a vertical direction.

One object of the invention is to provide a method for filling the bag which consists in 10 supporting the bag upon a platform in a manner to allow a passage of the spout through the support, filling the bag while lowering the support and platform, and then arresting the movement of the support, and 15 disengaging the filled bag by continued motion of the platform in the same direction and away from the support from beneath. Another object of the invention is to provide 20 an arrangement whereby a bag supporting element normally arranged in fixed relation to and above the movable platform, when the platform is moving toward the spout, is caused to be arrested during a portion of the downward movement of the platform away 25 from the spout, to permit withdrawal of the filled bag from its support by continued movement in the same direction.

Features of the invention include all the 30 details of construction, as well as the general arrangement of the parts for the purpose in hand. It is to be understood that it is not the intention to limit the invention to the details of construction, although these 35 are considered to be a part of the invention, as one means of carrying it out.

Other objects are to provide means whereby the bag is supported laterally during the filling operation by a flexible apron; to provide 40 means whereby upon completion of the filling operation, as the filling platform travels to unloading position, the bag is partially or completely withdrawn from the apron; to provide a series of bag supporting annulae alternately attachable, to receive 45 bags of different sizes; to provide a bag supporting structure mounted for instant removal; to provide means whereby the continued movement of the filled bag, disengages 50 the same from within the flexible bag-supporting device, or apron.

Advantages of the device will be disclosed in description of the drawings forming a part of this application and in said drawings:

Figure 1 is a front elevation showing the

platform in its lowermost position, with a bag arranged over the bag support;

Figure 2 is a vertical section on line 2—2 of Figure 1, but showing the platform substantially at its uppermost position, and with the bag support, apron and bag encircling the filling spout;

Figure 3 is a view partly in section, corresponding to Figure 1, but showing the platform at a position lower than shown in 65 Figure 2, with the extensions of the bag-support engaging, to temporarily prevent further downward movement of said support, and with the bag substantially filled;

Figure 4 is a sectional plan view on line 70 4—4 of Figure 3;

Figure 5 is a vertical sectional view of the loop-like bag support, showing the manner of attaching the apron thereto;

Figure 6 is a plan view of one size of a 75 loop-like bag support; and

Figure 7 is a plan view of another size, a series of loop-like bag-supports of different sizes being provided.

The numeral 1 designates vertical guides, spaced (see Figures 1 and 2) to slidably receive a platform-carrying element 2, said element being arranged to reciprocate substantially as shown. Carried by the element 2, is a platform 3 horizontally arranged and projecting outwardly. The numeral 4 represents the filling spout, 5 the screw shaft and 6 the screw. The elements just described are sufficient to illustrate the invention, and show a bag filling mechanism including a filling spout, and a bag supporting platform movable toward and away from the spout.

The method of carrying out the invention consists in providing a bag-supporting element carried by and movable with the platform, but separable from the platform, the movement of which support is arrested during a portion of that time when the platform and support are receding from the spout. This to provide a continued motion of the bag in a direction away from the support, to free the bag from said support.

In carrying out the invention, a bag-supporting element 10 is adjustably mounted and spaced above the platform to occupy a fixed relation with the platform as the same moves toward the spout, the support being arranged to be traversed by the spout. This element 10 is of loop-like configuration and

is sometimes referred to as an annulus. Means is provided to hold the loop in spaced relation above the platform, and in this instance comprises a guide (or guides) 12 as an upright tubular member. Each annulus or loop 10 is provided, in this instance, with a pair of downward extensions 15 each having a socket 16, and each arranged at the outer side of the loop on a circumference 16 concentric with its vertical axis. The socket members 15 are formed integrally with the loop, the outward downwardly slanting connecting element being shown at 19. The upper end of the member 12 and the lower end 15 of the element 15 normally abuttingly engage as shown. It is conceivable that the single member 15 may be used. Connected in the socket 16 is an extension 20 traversing the guides and reaching downwardly below the platform. These extensions in this instance are shown as cylindrical rods, the lower ends of which are adapted under certain conditions to impinge against a stop to temporarily arrest the movement of the bag support during the movement of the platform away from the spout. Either one or a plurality of these elements may be considered simply as a part of the annulus, the idea being to provide means for engaging the bag support to arrest its downward movement under conditions herebelow more fully described.

The apron is indicated at 25 and is secured, in this instance, to the outer side of the annulus by suitable means indicated at 26, a groove 27 being provided to receive the upper end of the apron. The apron is disposed substantially as shown in Figures 1, 2 and 3 and provides means for supporting the sides of the bag during filling and also provides flexible means from which the filled bag may be easily withdrawn in a downward direction. The interior surface of the fabric of which this hood or apron is composed, may be treated to reduce friction, at the same time retaining the flexible quality of the fabric.

A movable stop 35 is arranged in the path of the rod or rods to arrest movement of the annulus after the filling operation and means is also provided to move the stop to permit continued motion of the annulus in the same direction, the arrangement being such that the annulus is held until the filled bag is substantially free from the lower end of the apron. In this instance, connections are provided by which stop control means is actuated by the weight of the filled bag when drawn from the platform, the stop then being operated to permit follow-down motion of the bag support toward the platform, and against the bag supporting, holding or abutment means 12. This stop means is arranged above a socket or sockets formed in this instance by tubular members 30, ex-

tending below the floor 31. The stop means as a plate 35 is arranged so that it may be moved over these sockets to prevent entrance of the rods 20 thereinto. The stop position is shown in Figure 3. This stop means is 70 slideable upon a base plate 40 which plate is provided with a pair of vertical abutments 41 against which the forward edges 42 of the stop member impinge, when closing the sockets to the entrance of the rods 20. 75 This plate has an integral extension 45 to which is pivoted a lever 46 the pivot being shown at 47. The lever is of such length as to extend outwardly beyond the platform, when said platform is in its lowermost position. Upon the outer end of the lever is arranged an auxiliary platform 50, said platform being suitably connected to the lever 46.

The lever 46 is provided with a depending extension 55, and a rod 56 is pivoted as at 57 to this extension. This rod traverses the element 45 horizontally and is slideable therein, and has its opposite end traversing an upstanding lug 60 of the stop element 35. Suitable nuts 61 secure the rod to the stop. An additional abutment 65 acts to limit outward movement of the rod 56, and a coil spring 66 is interposed between the base plate 40 and the extension 55 to normally hold the stop over the socket, and to dispose the auxiliary platform 50 in a position to receive a filled bag when dragged in a direction outwardly from the platform. It will be understood that when the bag is deposited upon the element 50 the stop member 35 will be translated in a manner to permit the rods to enter into the sockets 30, and thus allow the loop-like bag support to be lowered to the initial position shown in Figure 1.

A method of and apparatus for filling a bag is thus provided in which the platform is movable toward and away from a spout, and in which a bag-supporting element is carried by and movable with the platform so that the motion of the bag supporting element can be temporarily arrested when receding from the spout, and so that the motion of the bag may be continued in a direction away from the support and spout, in this instance to separate the bag from the support and apron by movement downwardly therefrom. This is a decided improvement over the device ordinarily used inasmuch as the bag can be removed in a direction downwardly from the support, in a manner to automatically be freed from the support during its travel to unloading position.

The use of a loop-like member having small vertical height provides a very cheap and efficient means for supporting the bag during the filling operation, and this loop-like support in combination with the flexible apron is found to operate most satisfactorily. Important advantages of the present construction are cheapness of manufacture, op-

erating costs, and saving of time required to disengage the filled bag from its reinforcing support.

Operation.

With the platform 3 at its lowermost or unloading position, and with the annulus resting upon the guides and thus spaced from the platform, a bag A, wrong side out, 10 is slipped downwardly over the annulus with its bottom engaging upon the top of the annulus. In this position the annulus extensions 20 are within the sockets, and resting upon the cushions 70 or under some conditions 15 the cushions may be dispensed with. In any event, at this time the rods are engaged within their sockets, and the annulus is substantially at its lowermost position.

The platform is now caused to rise to filling 20 position, during which movement the bag is engaged with the filling spout, the spout traversing the annulus and apron to cause the bag to be forced downwardly through or within the annulus and apron as 25 shown in Figure 2 and to be turned right side out. During this upward movement, the rods are disengaged from their sockets, and when the platform reaches its uppermost or filling position, the bottom ends of 30 the rods are at a level above the stop plate, substantially as shown, and the stop plate has closed the sockets to the entrance of the rods.

Filling now begins and the platform 35 travels downwardly, the bag A stretches, but is laterally supported by the flexible apron 25. During the filling operation the rods have traveled downwardly with the platform and substantially at the end of the filling operation, see Figure 3, the lower ends of the 40 rods engage the stop at the upper side, thus preventing further downward movement of the annulus and apron. As the platform continues its downward motion, the bag is 45 withdrawn from the apron and by the time the platform reaches unloading position the top of the bag is substantially clear of the apron. When the platform reaches unloading 50 position, or even before, the bag can be removed. In this instance the arrangement is such that when the bag is dragged off of the main platform on to an auxiliary platform, the depression of the auxiliary platform 55 by the bag moves the stop plate, to the left, see Figure 4, to permit the rods to enter the sockets and allow the annulus to drop substantially to a position shown in Figure 1, in which it and the apron are disposed in spaced operative relation to the platform. Thus the operative cycle is 60 complete and the parts are positioned to receive another bag.

One of the important features of the invention is the use of a flexible bag support 65 which will allow the bag to spread circum-

ferentially during the filling operation. The outer dimensions of the ring 10 and its attaching elements 19 are such that the unfilled bag may be slipped downwardly thereover, in circumscribing relation. Therefore, the 70 apron must be of collapsible material so that when the bag is drawn over the annulus and apron, said apron can be circumferentially contracted, and so that when the bag is filled it may again be circumferentially expanded. 75 This arrangement can be clearly seen by comparing Figures 1 and 3. In Figure 1, the apron is supposedly circumferentially contracted while in Figure 3 it is circumferentially expanded. By this arrangement the 80 annulus is of such an outer dimension as to allow the bag to be pulled downwardly thereover, and the apron is of such circumferential dimension as to allow the bag to expand outwardly beyond the outer surface of the 85 annulus after passing through said annulus.

I claim as my invention:

1. A method for filling a bag by means of a mechanism including a spout, a platform movable toward and away from the spout 90 and a bag supporting element carried by and movable with the platform, which consists in arresting the motion of the bag supporting element when receding from the spout, while continuing the motion of the bag in a direction away from the support and spout. 95

2. A method for filling a bag by means of a mechanism including a spout, a platform movable toward and away from the spout and a bag supporting element carried by and 100 movable with the platform, which consists in temporarily arresting the motion of the bag support, while continuing the motion of the bag.

3. A method of filling a bag which consists in supporting the bag to move toward and away from a filling spout, in a manner to allow the passage of the spout through the support and into the bag, filling the bag while moving the support away from the 105 spout, then temporarily arresting the movement of the support, to disengage the filled bag therefrom. 110

4. A method of filling a bag which consists in supporting the bag to move toward and away from a filling spout, in a manner to allow the passage of the spout through the support and into the bag, filling the bag while moving the support away from the 115 spout, then arresting the movement of the support to disengage the filled bag therefrom by continued motion of the bag in the same direction and away from the spout and support. 120

5. In combination with a bag filling mechanism including a filling spout and a bag-supporting platform movable toward and away from the spout, a bag-supporting element adjustably mounted above the platform to occupy a fixed relation with the 125 130

platform as said platform moves toward the spout, said support adapted to be traversed by the spout, and having an extension, and a movable stop against which said extension will impinge to arrest the movement of the bag-support extension during movement of the platform away from the spout.

6. In combination with a bag filling mechanism including a filling spout and a bag-supporting platform movable toward and away from the spout, a bag-supporting element adjustably mounted above the platform to occupy a fixed relation with the platform, said support adapted to be traversed by the spout, and having an extension, and a movable stop against which said extension will impinge to temporarily arrest the movement of the bag-support extension to permit withdrawal of the bag from the support by continued movement in the same direction.

7. A device of the class described including a bag-filling spout and a platform movable away from and toward the spout, a guide upon the platform, a bag-support arranged to abut the guide and when so arranged adapted to be traversed by the spout, said support having an extension slidable in the guide, a socket arranged to slidably receive the extension, means movable to prevent entrance of the extension into the socket and thus arrest motion of the bag-support extension, as the bag is withdrawn as a result of continued motion of the platform.

8. A device of the class described including a bag filling spout and a platform movable away from and toward the spout, a guide upon the platform, a bag support arranged to abut the guide and when so arranged to be spaced above the platform in a manner to be traversed by the spout, said support having an extension slidable in the guide, a flexible apron circumscribing, attached to and depending from the support, adjustable means movable to arrest motion of the bag-support extension while the bag is withdrawn therefrom as a result of continued motion of the platform.

9. In combination with a bag filling mechanism including a filling spout and a platform movable toward and away from the spout, a bag-support upon the platform, movable with and also independently of the platform, adjustable means movable to be engaged by a portion of the bag-support to arrest motion thereof of said support while the bag is being withdrawn therefrom as a result of continued motion of the platform.

10. In combination with a bag filling mechanism including a filling spout and a platform movable toward and away from the spout, a bag-support arranged over the platform and slidably adjustable thereon, and disposed to be traversed by spout, ad-

justable stop means arranged to arrest downward movement of the support, after the filling operation, and means for operating the stop means to allow continued motion of the support in the same direction. 70

11. In combination with a bag filling mechanism including a filling spout and a platform movable toward and away from the spout, a loop for supporting the bag, said loop arranged above the platform for traversal by the spout and having rods projecting through the platform, abutment means to hold the loop in spaced relation above the platform, tubes to receive the rods, movable stop means arranged over the tubes with which the rods are engageable to arrest downward motion of the loop during continued downward motion of the platform, and means for moving the stop means to release the rods. 75 80 85

12. In combination with a bag filling mechanism including a filling spout and a platform movable toward and away from the spout, a bag supporting element traversable by the spout and arranged above the platform to positively occupy a fixed relation therewith as the platform moves toward the spout, an extension connected with the bag supporting element, and a movable abutment against which said extension impinges after the filling operation to arrest the movement of the bag support, and permit withdrawal of the bag from the support as the platform recedes from the spout. 90 95

13. In combination with a bag filling mechanism including a filling spout and a platform movable toward and away from the spout, a guide carried by the platform, an annulus of a size to be traversed by the spout, said annulus having a rod slidable in the guide and projecting below the platform, said guide acting as an abutment to space the annulus vertically above the platform, a socket below the platform to slidably receive the rod, a movable stop to temporarily prevent entrance of the rod into the socket, and means connected to move the stop and permit lowering of the rod into the socket. 100 105 110

14. A device of the class described comprising a vertically movable platform and a filling spout, said platform having guides, an annulus arranged above the guides and platform and having rods slidable in the guides, said annulus adapted to abut the guides to operatively position the annulus in relation to the platform, a flexible apron circumscribing, attached to and depending from the annulus, tubular sockets arranged to slidably receive the rods and limit downward movement thereof, means arranged to prevent entrance of the rods within the sockets in order to arrest motion of the annulus during continued motion of the platform toward unloading position, means ad- 115 120 125 130 135

jacent the unloading position of the platform to receive the filled bag, said means connected with the stop for moving the same from stopping position as the depressible means receives the bag.

15. In combination with a bag filling mechanism including a filling spout and a platform movable toward and away from the spout, a loop as a bag-supporting element arranged above the platform and having an extension projecting below the platform, abutment means to hold the bag support spaced above the platform during movement toward the spout, a movable stop with which the extension is engageable to temporarily arrest motion of the bag support when the platform is traveling away from the spout, and means for moving said stop to permit subsequent follow-down motion of the bag support, toward the platform and against the bag-support holding means.

16. In combination with a bag filling mechanism including a filling spout and a platform movable toward and away from the spout, a loop as a bag supporting element traversable by the spout and arranged above the platform, said loop having a flexible apron, extending toward the platform and said loop being arranged to permit movement of the platform independently thereof.

17. A device of the class described comprising a vertically movable platform, a loop as a bag-support arranged above the platform, a flexible apron depending from the loop, both loop and apron being traversable by the spout.

18. In combination with a bag filling mechanism including a filling spout and a platform movable toward and away from the spout, a guide carried by the platform, an annulus having a rod slideable in the guide, said annulus of a size to be traversed by the spout, an apron circumscribing the annulus and depending therebelow, said guide acting as an abutment to dispose the annulus in bag supporting position, a movable stop arranged in the path of the rod to arrest movement of the annulus after the filling operation and means connected to move the stop to permit continued motion of the annulus in the same direction, the arrangement being such that the annulus is held until the

filled bag is substantially free of the lower end of the apron.

19. In combination with a bag filling mechanism including a filling spout and a platform movable toward and away from the spout, a bag supporting annulus slidably adjustable upon the platform and movable in unison therewith during the filling operation, a spout arranged to enter the annulus, and means for arresting motion of the annulus after the filling operation, said means operable to allow continued motion of the annulus in a downward direction.

20. A device of the class described comprising a loop-like bag support, having a flexible apron attached thereto, and adapted to occupy a depending position when the loop is horizontally arranged.

21. A device of the class described having a bag support comprising an annulus, and a flexible collapsible tubular hood secured to the annulus, the external dimensions of the annulus being such as to permit a bag to be drawn downwardly thereover.

22. A device of the class described having a bag support comprising an annulus, and a tubular hood secured to the annulus, the external dimensions of the annulus being such as to permit a bag to be drawn downwardly thereover, and said apron being collapsible to permit such disposition of the bag in circumscribing relation to the entire support.

23. A device of the class described having a bag support comprising an annulus, the external dimensions of the annulus being such as to permit a bag to be drawn downwardly thereover, in circumscribing relation.

24. A device of the class described comprising a loop-like bag support having a flexible collapsible apron attached thereto, the outer dimension of the loop-like support being greater than the circumferential dimension of the bag.

25. A device of the class described comprising a loop-like bag support having an extension for operatively attaching it, the circumferential dimensions of the loop and extension being such as to allow a bag to circumscribe them.

In witness whereof, I have hereunto set my hand this 17th day of February 1927.

DANIEL BELCHER.
